UNITED STATES PATENT OFFICE.

WALTER JAMES THOMAS MCLEAN, OF MELBOURNE, VICTORIA, AUSTRALIA, ASSIGNEE,
BY DIRECT AND MESNE ASSIGNMENTS, TO THE M. B. RAIL ANCHOR PTY. LTD., OF
MELBOURNE, VICTORIA, AUSTRALIA, A CORPORATION OF VICTORIA.

ONE-PIECE RAIL ANCHOR.

Application filed February 24, 1923. Serial No. 320,889.

To all whom it may concern:

Be it known that I, WALTER JAMES THOMAS MCLEAN, subject of the King of Great Britain, residing at Melbourne, Victoria, Australia, have invented certain new and useful Improvements in One-Piece Rail Anchors, of which the following is a specification.

My invention relates to an improved one piece anchor for application to the rails of a railway in order to prevent or minimize the longitudinal movement or "creeping" which occurs where, as in the case of a double line, traffic on a particular track forming portion of a railway is normally conducted in one direction only.

The object of the present invention is to provide a strong, durable and portable device which will prevent or minimize such creeping by gripping the rail more firmly than devices hitherto known; which may be applied to a rail by one man with a hammer only; and which will be inexpensive and manufactured at one heating only.

In this specification the term "forwards" means in the direction of travel of the train, and the term "outwards" means in a direction away from the centre line of the rail. These terms being defined, the meanings of the terms "backwards" and "inwards" will be obvious.

I attain these objects by the device illustrated in the accompanying drawings, in which:—

Fig. 1 is a front elevation of the anchor in position looking backward (i. e. against the direction of travel of the train) the rail being shown by chain lines;

Fig. 2 is a plan of the anchor in position, showing the abutment on a sleeper and omitting the rib for clearness;

Fig. 3 is a side elevation of the anchor.

For the sake of simplicity the details of design will be described conjointly with the method of construction in the following paragraphs.

From a relatively long and narrow rectangular plate 1 of suitable dimensions composed of some resilient metal, preferably spring steel, an inverted-T shaped portion 50 of metal is cut so that the distance from the centre line of the resultant slot to the left hand edge of the plate in Fig. 1 is approximately double the distance which intervenes between the said line and the

right hand edge of the plate. The result of this operation is that there are formed on the right hand portion of the said plate two opposite tongues 3, 4 of metal situated above a slot 2 of slightly larger dimensions than, but corresponding in shape with, the base of the rail to which the anchor is to be applied. These tongues are referred to hereinafter as gripping tongues.

In order to allow the plate to be fitted on to the base of a rail the gripping tongue 65 3 is bent backwards and the gripping tongue 4 forwards in approximately parallel directions to an angle of about 60 degrees with the body 5 of the plate.

To fit the plate on to the base of a rail it 70 is first turned until the gripping tongues are parallel to the rail and is then raised and given a partial turn so as to bring the gripping tongues into engagement with the bevels 6 of the rail flange. To ensure that 75 each gripping tongue will, in all circumstances, grip the beveled portions of the rail flange as tightly as possible a small boss 7 is provided beneath the end of each tongue. When the anchor, as so formed, is 80 fitted to a rail it will be apparent that the bosses 7 bear very firmly upon the bevels 6 of the rail and in consequence were the rail to move forward longitudinally the anchor would be carried with it. The under-cutting of the gripping tongues also enables the end of a lever instrument to be inserted if desired when positioning the anchor on a rail flange of extra thickness.

To prevent or minimize this creeping of 85 the rail in relation to the sleepers an abutment arm 8 is provided integral with the anchor body and inclined forwardly and outwardly in relation thereto. The arm 8 ends in an abutment 9 which is adapted to 90 bear against the side of the sleeper 10, next in front of it so that when the rail tends to creep the said abutment will be forced against the side of the sleeper. In consequence the tendency of the rail so to move forward will be overcome as any increase of the force tending to produce creeping will simultaneously increase the twisting moment of the anchor body and consequently will tend to force the bosses 7 further up the bevels 6 and thus grip the rail more firmly. The angle of the bend at the junction of the abutment arm 8 and anchor

body 5 is formed at a little distance from the base of the tongue 3 while that at the junction of the arm 8 and abutment 9 is formed at such point on the said arm as is deemed suitable having regard to the size of the abutment required. As the full width of the metal in the said plate is available for the formation of the arm and abutment they will respectively be of sufficient strength to withstand any ordinary forces operating to bring about the creeping movement above mentioned.

It will be noticed (see Fig. 3) that the abutment 9 is not vertical but has a slight forward inclination toward its lower edge and that the gripping tongue 3 is downwardly inclined. These features are designed so that the tongues are pressed against the bevels of the rail flange when in position, and when the abutment is forced against a sleeper 10 it is brought into a vertical position (see Fig. 2) causing the anchor to be slightly twisted and the gripping tongue 4 to be still more firmly pressed against the bevel of the rail flange. Any tendency to raise the tongue 3 by this twisting will be neutralized by the downward inclination of this tongue.

In order to strengthen the anchor it is provided with a lateral rib 11, extending across the anchor body from a point outside the gripping arm 4 to a point about midway along the abutment arm. The rib may be formed either as a corrugation or as a thickened portion.

From the foregoing description of this invention it will be realized that this improved anchor may be applied to a rail by one man using an ordinary hand hammer, and that the various processes of cutting out the T-portion, forming the bosses, forming the rib, bending the gripping tongues, and forming the said arm and abutment may all be performed at one heating of the plate, and the necessity of submitting the plate to a number of different processes in the course of its manufacture may be avoided with ease.

I am aware that one well known form of rail anchor is formed from a relatively long and narrow rectangular plate of suitable dimensions by cutting therefrom an inverted-T shaped slot at one side of the centre line and the narrow tongues of metal so formed above the slot are then bent—the one forwardly, and the other backwardly—until the shortest distance between these parallel tongues is slightly greater than the width of a rail flange. The metal tongues bear on the bevels of the rail flange when the anchor is in position. The longer side portion of the anchor plate, hereinbefore designated the abutment arm, is cut away at its upper edge and bent forward and inward through about 180 degrees until approxi-

mately parallel with the body of the anchor. When in position the abutment passes under the rail flange and bears against an adjacent sleeper. This type of anchor, as previously designed, required a special tool, and the services of two men, for its attachment.

The terms "recessed vertical body plate" and "recessed body" as hereinafter used, refer to a body plate from the upper portion of which an inverted-T or similarly shaped portion of metal has been cut away so that the plate will accommodate the base flanges of the rail and will have an integral tongue of metal above each rail flange.

I claim:

1. The combination, in a one piece rail anchor, of a recessed vertical body plate having oppositely bent gripping tongues, with a side extension in substantially the same horizontal plane as the body plate and forwardly directed to form an abutment arm positioned outwardly from the rail flange in use.

2. The combination, in a one piece rail anchor, of a recessed vertical body plate having oppositely bent gripping tongues, with a side extension of substantially the full width and depth of the body plate and forwardly directed to form an abutment arm positioned outwardly from the rail flange in use.

3. The combination, in a one piece rail anchor, of a recessed body, oppositely bent gripping tongues, and a forwardly directed abutment arm integral with one side of the body and having an end abutment portion bent outwardly and inclined forwardly in a vertical plane.

4. The combination, in a one piece rail anchor, of a recessed body, oppositely bent gripping tongues, a boss beneath the end of a gripping tongue and an inclined abutment on an arm integral with one side of the body.

5. The combination, in a one piece rail anchor, of a recessed body, oppositely bent gripping tongues, a boss beneath the end of each gripping tongue and a vertically inclined abutment on an arm integral with one side of the body.

6. The combination, in a one piece rail anchor adapted to be stamped out and completed in one heating operation from steel, of a recessed vertical body, oppositely bent gripping tongues, an abutment arm integral with one side of the body, and a rib on the body and abutment arm in a relatively horizontal position.

7. The combination, in a one piece rail anchor adapted to be stamped out and completed in one heating operation from steel, of a recessed vertical body plate having oppositely bent gripping tongues, with a side extension in substantially the same horizontal plane as the body plate and forwardly directed to form an abutment arm positioned in

outwardly from the rail flange in use, a rib on the body plate and abutment arm in a relatively horizontal position.

8. The combination, in a one piece rail anchor, of a recessed body, oppositely bent gripping tongues, a boss beneath the end of each gripping tongue, and a forwardly directed abutment arm integral with one side of the body and having a vertically inclined abutment portion bent outwardly.

9. The combination, in a one piece rail anchor, of a recessed body, oppositely bent gripping tongues, a boss beneath the end of each gripping tongue, and a forwardly directed abutment arm integral with one side of the body and having an abutment portion

bent outwardly and inclined forwardly in a vertical plane.

10. The combination, in a one piece rail anchor, of a recessed body, a lateral rib on the body, oppositely bent gripping tongues, a boss beneath the end of each gripping tongue, and a forwardly directed abutment arm integral with one side of the body and having an abutment portion bent outwardly and inclined forwardly in a vertical plane.

In testimony whereof I affix my signature.

WALTER JAMES THOMAS McLEAN.
